[57] CLAIM

The ornamental design for a surface for a chair back, as shown and described.

DESCRIPTION

FIG. 1 is a rear elevational view of the surface for a chair back wherein the outline of the chair is shown in dotted outline;

FIG. 2 is a perspective view of the rear and one side of the surface for a chair back of FIG. 1.

The fragmented crossed lines represent fabric and is understood to be continuous throughout. The broken lines on the pockets and the straps represent stitching.
